CLAIM

The ornamental design for an end cap for shower curtain rod, as shown and described.

DESCRIPTION

FIG. 1 is a front, right, top perspective view of an end cap for shower curtain rod, showing my new design;

FIG. 2 is a rear, left, bottom perspective view thereof;

FIG. 3 is a front elevational enlarged view thereof;

FIG. 4 is a rear elevational enlarged view thereof;

FIG. 5 is a left-side view enlarged thereof;

FIG. 6 is a right-side enlarged view thereof;

FIG. 7 is a top plan view thereof; and,

FIG. 8 is a bottom plan view thereof.

The broken lines in the drawings depict portions of the end cap for shower curtain rod that form no part of the claimed design.
